DESIGN FOR A PACK FOR FRAGILE ARTICLES

Ernest L. Shepard, Fairfield, Maine, assignor, by mesne assignments, to The Canal National Bank of Portland, Portland, Maine, trustee, a national banking association

Application April 16, 1945, Serial No. 119,019

Term of patent 14 years

(Cl. D58—13)

To all whom it may concern:

Be it known that I, Ernest L. Shepard, a citizen of the United States, residing at Fairfield, in the county of Somerset, State of Maine, have invented a new, original, and ornamental Design for Pack for Fragile Articles, of which the following is a specification, reference being had to the accompanying drawing, forming part thereof.

Fig. 1 is a perspective view of a pack for fragile articles showing my new design, the pack being open, and

Fig. 2 is a similar view, the pack being closed.

I claim:

The ornamental design for a pack for fragile articles, as shown.

ERNEST L. SHEPARD.
